(57) **CLAIM**

The ornamental design for a slab comprising particulate mineral mixture, as shown and described.

DESCRIPTION

The file of this patent contains at least one drawing/photograph executed in color. Copies of this patent with color drawing(s)/photograph(s) will be provided by the Office upon request.

The sole FIGURE is a top plan view of a slab comprising particulate mineral mixture, showing our new design.

The broken lines represent portions of the slab that form no part of the claimed design.
